[73] Assignee: Novitas, Inc., Santa Monica, Calif.

[57] CLAIM

The ornamental design for a housing for a one-way
ultrasonic ceiling sensor, as shown and described.

DESCRIPTION

FIG. 1 is a rear elevational view of the housing for a
one-way ultrasonic ceiling sensor showing our new
design;

FIG. 2 is a bottom plan view thereon;

FIG. 3 is a top plan view thereof;

FIG. 4 is a front elevational view thereof; and,

FIG. 5 is an end elevational view thereof, the opposite
end being a mirror image.
